TRAVERSE ROLL

Wilhelm Reiners, Gladbach-Rheydt, Germany,
assignor to Schlafhorst & Co., Gladbach-
Rheydt, Germany, a firm of Germany

Application March 9, 1940, Serial No. 323,087
In Germany February 17, 1939

7 Claims. (Cl. 242—26)

This invention relates to a traverse roll for winding yarn, thread, wire or similar strand materials.

The co-pending application for United States Letters Patent, Serial No. 212,674, filed June 9, 1938, describes traversing means for winding machines wherein the yarn is moved back and forth for the purpose of winding it in helical coils by two separate devices, one of which moves the yarn in one direction, while the other causes a return movement of the yarn. The device which moves the yarn forward consists of a helical groove provided upon a traverse roll which may contact the cop, cone or package upon which the yarn is wound. The device which causes the return movement of the yarn consists of a thread guide which is situated outside of the space limited by planes extending through the side surfaces of the cop, cone or package. Both devices have been constructed on the basis of the principle that if a thread is tangentially guided to a rotating spindle, and if that part of the thread which is situated at a distance from the rotating spindle is shifted sidewise, then the thread will be wound upon the spindle in helical coils until it reaches a position situated directly opposite the point to which said part of the thread has been shifted.

It was found that these devices operate with great efficiency when carrying out the so-called firm winding of cops and packages in the course of which the yarn, while being wound, is under a comparatively great tension and is pressed against a larger part of the circumference of the traverse roll. These devices avoid the necessity of using intersecting grooves and of special complicated construction of the points in intersection. In several instances, however, it is necessary to wind the yarn softly or loosely, i. e. while subjecting it to a comparatively small tension. Loosely wound packages or cops are required for instance, in the dye industry.

It was found that in the case of a loose winding, the thread guide does not always suffice to cause the proper helical winding of the weakly tensioned yarn, and that sometimes, in spite of the proper position of the thread guide, the yarn does not follow the predetermined helical path upon the traverse roll in the course of the return movement. This can also happen when the yarn is moved with a particularly great speed, when the traverse roll is of a comparatively small diameter, and/or has a very smooth surface, or when the yarn is slippery or highly greased.

An object of the present invention is the pro-

vision of yarn winding means which are so constructed that the correct winding of the yarn will take place even if the yarn is subjected to small tension.

5 A further object is to improve the construction described in the aforesaid patent application by the provision of additional means enabling it to operate efficiently in the course of the return movement of the yarn.

10 Further objects of the present invention will become apparent in the course of the following specification.

The objects of the present invention may be realized by combining the aforesaid yarn-reciprocating means consisting of a single helical groove provided upon the traverse roll and a thread guide with an auxiliary device causing the yarn to wind itself in the form of proper spiral coils in the course of its return movement.

15 In accordance with the present invention, this auxiliary device cooperating with the thread guide, consists of a few projections of light weight made, for instance, of hard metallo-ceramic materials. These projections may have the form of pins or the like, carried by the traverse roll and situated on the sides of the path of the yarn upon the traverse roll in the course of the correct return movement of the yarn, so that they act as abutments preventing the yarn from slipping.

20 In machines wherein the traverse roll is used for driving the bobbin, the pins may be resiliently mounted in bore holes provided in the traverse roll, so that they are moved either partly or totally within the traverse roll while that part of the traverse roll wherein the pins are located is moved into contact with the bobbin.

25 The invention will appear more clearly from the following detailed description when taken in connection with the accompanying drawings showing by way of example preferred embodiments of the inventive idea.

30 In the drawings:

Figure 1 is the top view of a device constructed in accordance with the principles of the present invention and used for winding a bobbin;

Figure 2 is a front view of the device shown in Figure 1;

Figure 3 is a side elevation of the device shown in Figures 1 and 2; and

Figure 4 is a section through a part of a traverse roll shown in Figures 1, 2 and 3.

The device shown in the drawings comprises a spool 20 having a support 21 upon which the yarn or strand 22 is wound. This spool is wound

upon a bobbin 23 which includes a shaft 24 pivotally mounted upon a lever 40 connected with a frame 28.

The bobbin 23 is driven by contact with the traverse roll 30, the outer surfaces of which may be made of a ceramic material, such as a steatite or soapstone.

The traverse roll 30 is firmly connected with a shaft 31 which is mounted upon the frame 28. The shaft 31 is driven by any suitable mechanism (not shown).

The spool 20 and the thread guide 29 which stretches the yarn 22 are situated outside of the space which is limited by two planes passing through the two side surfaces of the bobbin 23 and diagrammatically indicated by the lines $x-x$ and $y-y$ respectively. As shown in Figure 2, the thread guide 29 may be situated close to the plane $v-v$ passing through a side surface of the traverse roll 30.

A rod or abutment 33 is carried by the frame 28 and is used to limit the return stroke of the yarn 22.

The traverse roll 30 is provided with a groove 34 extending in the form of a single uninterrupted and unintersected helix substantially from one side surface of the roll 30 to the opposite side surface. The end 35 of the groove 34 is in communication with a short groove 36 extending in an opposite direction to the groove 35 and constituting the means of reversing the movement of the yarn 22.

The opposite end 37 of the helical groove 34 is in communication with another short groove 38 which extends in substantially the same direction as the reversing groove 36 and which may be designated as the receiving groove. The two grooves 36 and 38 are comparatively short. They do not have the form of a helix and in no way approach or intersect the helical groove 34.

The form and other particulars of the grooves 34, 36, and 38 are immaterial for the purposes of the present invention.

In accordance with the present invention, the traverse roll 30 is provided with a few pins 41 having projecting conical portions 42 and made of a metallo-ceramic material or the like. Each pin 41 is, preferably, of a circular cross-section and is situated in a bore hole 43 enclosed by a sleeve 44. A spring 45 encloses the pins 41 and presses against a plate 46 firmly connected with the pin and pressing against the edges 47 of the sleeve 44. The pins 41 are provided on the sides of the path of the yarn 22 upon the traverse roll 30 in the course of the return movement of the yarn. The pins project radially beyond the side surfaces of the roll 30 and are resiliently supported in this radial direction by the springs 45.

In operation, the yarn 22 engages the end 37 of the helical groove 34 and due to the rotation of the roll 30, is guided by the groove 34 until it completes its forward movement and reaches the end 35 of the groove 34. Since the shaft 24 is rotated, the yarn 22 will be wound in the form of a helical coil upon the bobbin 23. Then the yarn is shifted from the end 35 of the groove 34 into the groove 36. Due to the location of and the force exerted by the thread guide 29, the yarn 22 remains in an inclined position upon the roll 30 and is pulled out of the groove 36. Thereupon the yarn 22 carries out its return movement upon the smooth surface of the roll. The pins 41 prevent the slipping of the yarn upon the smooth surfaces of the traverse roll 30. Thus the proper winding of the yarn 22 upon the bob-

bin 23 in the form of intersecting helical coils will be assured, even though the yarn is subjected to comparatively weak tension, so that the coils of the bobbin 23 are quite loose. The return movement of the yarn is terminated by the abutment 33. The yarn slips into the receiving groove 38 and is moved into the end 37 of the helical groove 34.

Each of the pins 41 may be substituted by a plurality of pins or other projections, balls or the like.

It is apparent that the specific illustration shown above has been given by way of illustration and not by way of limitation and that the structure above described is subject to wide variations and modifications without departing from the scope or intent of the present invention.

What is claimed is:

1. Winding means, comprising in combination, 20 a cylindrical rotary traverse roll contacting a strand, a strand winding, said traverse roll having a helical groove formed therein for automatically shifting the strand to be wound upon said winding from one side surface of the traverse 25 roll to the opposite side surface thereof, and at least one projection extending outwardly from the cylindrical surface of said traverse roll and located in the path of the strand during its return movement for guiding said strand in the 30 course of its return movement; and means supplying the strand to the traverse roll and situated at one side thereof to cause the return movement of the strand.

2. In winding machines, a traverse roll having 35 a cylindrical surface adapted to contact a strand, a single uninterrupted and unintersected helical groove formed in said traverse roll for shifting the strand which is to be wound in helical coils upon a winding, from one end of the cylindrical 40 surface of said traverse roll to the opposite end thereof, and at least one projection extending outwardly from the cylindrical surface of said traverse roll and located in the path of the strand during its return movement for guiding said strand in the course of its return movement to the first-mentioned end of said cylindrical surface.

3. In winding machines, a traverse roll having 45 a cylindrical surface adapted to contact a strand, a single helical groove formed in said traverse roll for shifting the strand which is to be wound in helical coils upon a winding, from one end of the cylindrical surface of said traverse roll to the opposite end thereof, and projections extending 55 outwardly from said cylindrical surface and located close to the path of said strand upon the traverse roll in the course of its return movement which is caused by an inclination of said strand relatively to said traverse roll.

4. In winding machines, a traverse roll having 60 a cylindrical surface adapted to contact a strand, a single helical groove formed in said traverse roll for shifting the strand which is to be wound in helical coils upon a winding, from one end of the cylindrical surface of said traverse roll to the opposite end thereof, and projections extending outwardly from said cylindrical surface and located on the sides of the path of 65 said strand upon the traverse roll in the course of its return movement which is caused by an inclination of said strand relatively to said traverse roll.

5. Winding means, comprising in combination, 70 a cylindrical rotary traverse roll contacting a strand, a strand winding, said traverse roll hav-

ing a helical groove formed therein for automatically shifting the strand to be wound upon said winding from one side surface of the traverse roll to the opposite side surface thereof, and at least one projection of circular cross-section extending outwardly from the cylindrical surface of said traverse roll and located in the path of the strand during its return movement for guiding said strand in the course of its return movement; and means supplying the strand to the traverse roll and situated at one side thereof to cause the return movement of the strand.

6. In winding machines, a traverse roll having a cylindrical surface adapted to contact a strand, a single uninterrupted and unintersected helical groove formed in said traverse roll for shifting the strand which is to be wound in helical coils upon a winding, from one end of the cylindrical surface of said traverse roll to the opposite end thereof, and at least one pin con-

sisting of a metallo-ceramic material and projecting beyond said cylindrical surface for guiding said strand in the course of its return movement to the first-mentioned end of said cylindrical surface.

7. In winding machines, a traverse roll having a cylindrical surface adapted to contact a strand, a single uninterrupted and unintersected helical groove formed in said traverse roll for shifting the strand which is to be wound in helical coils upon a winding, from one end of the cylindrical surface of said traverse roll to the opposite end thereof, at least one pin projecting radially beyond said cylindrical surface for guiding said strand in the course of its return movement to the first-mentioned end of said cylindrical surface, and means resiliently supporting said pin in its radial direction.
